(57) **CLAIM**

The ornamental designs for a pair of pivotal nose pad assembly, as shown and described.

DESCRIPTION

FIG. 1 is a front perspective view of a pair of pivotal nose pad assembly shown in a first embodiment;

FIG. 2 is a front elevation view of the pair of pivotal nose pad assembly of FIG. 1;

FIG. 3 is a rear elevation view of the pair of pivotal nose pad assembly of FIG. 1;

FIG. 4 is a left side elevation view of the pair of pivotal nose pad assembly of FIG. 1;

FIG. 5 is a right side elevation view of the pair of pivotal nose pad assembly of FIG. 1;

FIG. 6 is a top plan view of the pair of pivotal nose pad assembly of FIG. 1;

FIG. 7 is a bottom plan view of the pair of pivotal nose pad assembly of FIG. 1;

FIG. 8 is a front perspective view of a pair of pivotal nose pad assembly shown in a second embodiment;

FIG. 9 is a front elevation view of the pair of pivotal nose pad assembly of FIG. 8;

FIG. 10 is a rear elevation view of the pair of pivotal nose pad assembly of FIG. 8;

FIG. 11 is a left side elevation view of the pair of pivotal nose pad assembly of FIG. 8;

FIG. 12 is a right side elevation view of the pair of pivotal nose pad assembly of FIG. 8;

FIG. 13 is a top plan view of the pair of pivotal nose pad assembly of FIG. 8; and,

FIG. 14 is a bottom plan view of the pair of pivotal nose pad assembly of FIG. 8.

The appearance of elements presented in broken line format form no part of the claimed design.

1 Claim, 6 Drawing Sheets
